UNITED STATES PATENT OFFICE.

WILLIAM R. MCCOLLOM, OF CHICAGO, ILLINOIS.

SWITCH-ROD.

1,141,129.

Specification of Letters Patent.

Patented June 1, 1915.

Application filed October 15, 1914. Serial No. 866,743.

To all whom it may concern:

Be it known that I, WILLIAM R. MCCOLLOM, a citizen of the United States, and a resident of Chicago, county of Cook, and State of Illinois, have invented certain new and useful Improvements in Switch-Rods, of which the following is declared to be a full, clear, and exact description.

This invention relates to switch rods, and 10 more particularly to the connecting rod between the switch stand and switch point.

Ordinarily, connecting rods are constructed of a single piece of metal and frequently great damage is done when a train runs 15 through a switch which is set against it, the result being that some part of the switch stand, or the connecting members between it and the switch points are broken, leaving the switch points disconnected from the 20 switch stand, so that if the train is backed up over the switch or another train is run over through the switch, further damage is done to the switch points, and the cars are liable to be derailed and overturned.

25 The object of this invention is to provide a connecting rod between the switch stand and switch point, arranged to temporarily hold the switch points in the position left by a train or car running through the switch 30 when set against it, so that when backing up over the switch or when a following train runs back over the switch, the switch points of the latter will be held in the position set by the train running through it.

35 To such ends, this invention consists in a connecting rod for switches, made in two parts slideable upon each other, and positively connected together by a breakable part, and having a frictional connection for 40 temporarily holding them in any position assumed when moved relative to each other, with sufficient force to break the breakable part.

45 It further consists in the several novel features of construction, arrangement and combination of parts hereinafter fully described and claimed.

The invention is clearly illustrated in the accompanying drawing, in which:—

50 Figure 1 is a side elevation of a switch rod embodying a simple form of the present invention and showing its connection with a switch stand and switch point; Fig. 2 is a side view of the same parts, but showing 55 the breakable part as having been broken by a train running through the switch when

set against it; Fig. 3 is a plan of the rod alone, looking from below; Fig. 4 is a detail cross section of the rod taken on line 4—4 of Fig. 1; and Fig. 5 is a detail longitudinal section taken on line 5—5 of Fig. 4.

Referring to said drawing, which shows one embodiment of the present invention, the reference letter, A, designates a switch stand of ordinary and well known construction, B, one of the rails of a railroad track, C, a switch point, and D, the connecting rod between the switch stand and switch point. In accordance with the common practice, the ends of the connecting rod, D, are 60 forked as at 10, 11, one end being attached to the switch throwing arm, 12, of the switch stand, and the other end being attached to the switch rod or parts, 13, which connects the two points of the switch. Preferably 65 the parts are connected by bolts, 14, passing through the forked ends of the connecting rod D, and arm, 12, and rod, 13, in accordance with the usual and customary practice. The 70 operation of a switch is well known and requires no particular explanation so far as 75 this specification is concerned. When the handle of the switch is moved through its stroke, the connecting rod is shifted in one direction, depending on the direction which 80 the switch handle is moved, and the switch points are therewith moved accordingly and 85 set positively by the operating mechanism of the switch stand, which, however, is liable to be broken, and, in fact, is broken, when 90 the switch points are forced back by a train running through the switch when set 95 against it.

The rod, D, which forms the subject matter of this invention, is formed of two members, 15, 16, the one being slidably connected with the other, and positively connected together against relative, lengthwise movement by a breakable connecting member, 17, that is to say, a connecting member formed 100 of suitable fragile material or of material of suitable form, which will render it more liable to breakage than any other parts of the rod or switch mechanism, whenever sufficient strain is put upon rod, D, to break 105 any part of the switch mechanism.

Preferably, the member, 15, of the connecting rod, D, comprises a rod having the fork, 10, upon one end, and sliding in a tubular part which comprises the member 110 16, of the rod, D, which members are of strong and substantial construction, and, if

desired, may be formed of malleable castings, or may consist of forgings. The two are positively connected against relative movement by the breakable connecting member, 17, which may be formed of cast iron or other comparatively fragile metal, of sufficient strength, however, to transmit motion between the two members, 15, 16, of the rod D, whenever the switch is thrown 10 properly. A simple means for securing the breakable member to the members 15, 16, may comprise lugs, 18, 18, two of which are formed on the member 15, near its forked end, and two on the member 16, near the 15 end adjacent said forked end of the member 15. The space between the forked end of the rod member, 15, and the adjacent end of the tube member, 16, is sufficient to permit the rod member, 15, to telescope into 20 the tube member, 16, a distance at least equal to the distance of the throw of the switch point. The breakable member 17, is preferably given a shape facilitating its breakage when subjected to undue strain, 25 and it is shown in the drawing as having a central, inverted U-shape bend merging into two upright U shape bends, which terminate into eyes, 19, 20. Said eyes are connected to the lugs, 18, 18, by headed pins, 21, excepting through registering holes in the lugs and eyes, and said headed pins have cotter pins, 22, on the ends opposite their heads to hold them in place. The three members, 15, 16, 17, constitute the switch 30 rod so far as it serves to throw the switch and perform the functions of a single piece switch rod, until the breakable part is destroyed.

The two members 15, 16, of the rod, D, 40 are further connected by means capable of holding them against relative lengthwise movement, but not positively, but serving to hold said two members in any position assumed when moved relatively to each other 45 in a lengthwise direction, as, for instance, when the breakable member is broken and the rod member, 15, is telescoped into the tube member, 16, or partly withdrawn therefrom. Said means may comprise one or 50 more curved, spring bars, 23, seated in recesses or depressions, 24, formed in the rod member, 15, and bearing against the internal face of the tube member, 16. Ordinarily, the springs, 23, extend lengthwise 55 of the rod; they are stiff enough, and bent to such an arc of a circle, prior to their being inserted between the two members, 15, 16, that sufficient friction is maintained between said two members to temporarily hold 60 them in fixed position against relative lengthwise movement, except, of course, if undue force is exerted to move them lengthwise of each other. Preferably, the spring or springs are set above the center of the 65 rod, but not on top thereof, and the lower

edges, 25, of the recesses slope downward to facilitate the discharge of any water that may possibly collect in said recesses, and one or more discharge orifices, 26, may be provided in the bottom of the tube member, 70 16, for the escape of the water, although this particular arrangement is not essential, so far as this invention is concerned.

In operation, when the switch is set against a train of cars, and the train runs 75 through the switch, the wheels force both switch points over, and inasmuch as the operating mechanism of the switch stand prevents the end of the switch rod, D, connected therewith, from moving, the switch point, through its connection with the other end of the switch rod, D, strains the breakable member to such an extent that it becomes broken (see Fig. 2), whereupon the member, 15, of the rod, D, which is connected to the switch points, is either pulled partly out from the tube member, 16, or pushed farther thereinto, as the case may be, and held in such position by the action of the spring, 23, thereby holding the switch 80 points in the position left by the wheels of the passing train, permitting said train or following ones to run back over the switch without disturbing the switch points and without danger of consequent damage to the 85 switch and train. A person attempting to throw the switch after the breakable member has been broken, may readily detect the break and can replace the broken member with a whole one, without much effort. 90

More or less variation of the details of construction shown and described, is possible without departing from the spirit of this invention. I desire, therefore, not to limit myself to said exact form and construction, 105 but intend in the following claims to point out all of the invention disclosed herein.

I claim as new and desire to secure by Letters Patent:

1. A switch rod comprising two members, 110 the one slidably connected to the other and having a breakable connection forming a positive connection therebetween, capable of being broken when subjected to undue strain, and a frictional element between said two 115 members for temporarily holding them in position when said breakable connection is broken.

2. A switch rod comprising two members frictionally secured together to resist relative lengthwise movement, one having a 120 slidable connection with the other, and, also, a positive connection therewith, comprising a comparatively fragile element.

3. A switch rod comprising two members, 125 one having a frictional, slidable connection with the other, and a curved, comparatively fragile, connecting member secured to and connecting said two members against relative lengthwise movement. 130

4. A switch rod comprising two members, one having a frictional, slidable connection with the other and a comparatively fragile connecting member secured to and connecting said two members against relative lengthwise movement, except when broken, said fragile member being formed with one or more reverse curved portions. 35
5. A switch rod comprising two members, one being movable lengthwise upon the other, a spring interposed between said two members for frictionally securing them together against relative lengthwise movement, and an additional, comparatively fragile, connecting member secured to and positively connecting said two members except when broken. 40
6. A switch rod comprising two telescoping members, arranged for connection with the throw mechanism of a switch stand and with an associated switch point, one of said members having one or more recesses formed therein, a curved spring seated in each recess and bearing against the other member to frictionally hold them against relative lengthwise movement, and a comparatively fragile, connecting member secured to and connecting said telescoping members, except when broken. 45
7. A switch rod comprising a tube member and a rod member slidably and frictionally secured in said tube member, the outer ends of said members being arranged for connection with the operating parts of a switch stand and switch point, respectively, and a comparatively fragile, connecting member secured to and positively connecting said tube and rod members, except when broken. 50
8. A switch rod comprising a tube member, and a rod member sliding therein, said members having a comparatively fragile connection therebetween, and having forked, outer ends for connection with the throw mechanism of a switch stand and with a switch point, a spring plate interposed between the internal face of the tube member and rod member, for frictionally connecting them against relative lengthwise movement. 55
9. A switch rod comprising a tube member and a rod member sliding therein, said members having a fragile, connecting member therebetween, and being also frictionally connected together, their ends being arranged for connection with the throw mechanism of a switch stand and switch point.
